UNITED STATES PATENT OFFICE.

EDWARD W. COUGHLIN, OF NEW YORK, N. Y.

SWITCH OPERATING AND LOCKING MECHANISM.

SPECIFICATION forming part of Letters Patent No. 737,354, dated August 25, 1903.

Application filed January 5, 1903. Serial No. 137,764. (No model.)

To all whom it may concern:

Be it known that I, EDWARD W. COUGHLIN, a citizen of the United States, and a resident of New York city, in the county of Richmond and State of New York, have invented certain new and useful Improvements in Switch Operating and Locking Mechanism, of which the following is a specification.

The invention relates to improvements in switch operating and locking mechanism; and it consists in the novel features, arrangement, and combinations of parts hereinafter described, and particularly pointed out in the claims.

15 In accordance with my invention I provide a simple mechanism for opening and closing railway-switches, for rigidly locking the switch-tongue in its adjusted position, for detecting to the operator handling the switch 20 any failure of the switch-tongue to attain its correct position for setting the signal-light in accordance with the condition of the switch and coöperating-rails, and for enabling the independent adjustment of the switch-rails 25 with respect to each other and to the rails with which they coöperate; and the object of my invention is to afford entirely efficient, convenient, and safe switch-operating mechanism.

30 The invention will be fully understood from the detailed description hereinafter presented, reference being had to the accompanying drawings, in which—

Figure 1 is a top view, partly broken away, 35 of a portion of a railway-switch and coöperating rails equipped with mechanism constructed in accordance with and embodying the invention. Fig. 2 is an enlarged longitudinal section of a portion of the switch moving and locking mechanism, with the detector-bar in its locking position, this section being on the dotted line 2 2 of Fig. 3. Fig. 3 is a vertical section of same on the dotted line 3 3 of Fig. 2. Fig. 4 is a top view of the box 40 or casing through which the detector-bar and switch-shifting bar passes. Fig. 5 is an enlarged detached side elevation of the switch-shifting bar. Fig. 6 is a vertical section of same on the dotted line 6 6 of Fig. 5. Fig. 7 45 is a top view of same. Fig. 8 is an enlarged detached side elevation of the cam-plates and link which coöperate with the shifting-bar for

unlocking the latter when the switch-rails are to be moved. Fig. 9 is a detached side elevation of the link connected with said cam-plates. Fig. 10 is a detached top view of the cam-plates and link shown in Fig. 8. Fig. 11 is a detached top view of the said link. Fig. 12 is a detached front elevation of the locking-bar coöperating with the said shifting-bar and cam-plates. Fig. 13 is a vertical section of same on the dotted line 13 13 of Fig. 12, Fig. 14 is a bottom edge view of same, and Fig. 15 is an enlarged top view of the adjustable head-rod which connects the two rail members of the switch and which is also connected with the shifting-bar presented in Figs. 5 and 7.

In the drawings, 20 21 denote the rails for the main line, and 22 23 the side-track rails, and the rail members 21 22 (shown in Fig. 1) comprise the switch members, which are connected together by the head-rod, the latter comprising the rod 24 and bars 25 26, which are respectively secured to the switch-rails 21 22 and 75 have outwardly-projecting guiding members 27 of usual character. The facing ends of the bars 25 26 are formed with the right-angular members 28, which are apertured to permit the passage through the same of the 80 inner threaded end of the rod 24, which is locked within said angular members 28 by means of the nuts 29 at the inner or facing sides of said members 28 and the nuts 30 at the outer sides of said members 28, and the 85 inner nuts 29 are locked against rotation when in their operative position by means of the laterally-bent lips 31 at the ends of said members 28. The switch-rails 21 22 are held a definite distance apart and their relation to 90 the rails 20 23 established by means of the head-rod, and it is obvious that the said rails 21 22 may be independently adjusted at will. One of the main purposes of this part of the invention is to enable the adjustment of the 95 switch-rail 21 with respect to the rail 23 without requiring any adjustment of the switch-operating mechanism proper. If it should be found that the switch-rail 21 is not in the proper adjustment with the rail 23, the nuts 100 30 for the bar 26 may be loosened or screwed from contact with the angular member 28 of said bar, and thereupon the bar 26 and rail 21 may be moved outwardly to the extent

then permitted by the new position of said nuts 30, after which the nuts 29 for said bar 26 will be moved to the position required for securing the new adjustment of the rail 21 5 and the bar 26 then moved up against said nuts 29, after which the nuts 30 will be again tightened against the said angular member 28 of the bar 26 for the purpose of rigidly holding the switch-rail 21 in its adjusted position. The adjustment of the rail 21 may be thus secured without disturbing or requiring any resetting of the switch-operating mechanism proper, and this is a feature of great advantage.

15 The rod 24 extends below and outwardly beyond the rail 23 and at its outer end is pivotally secured by a bolt 32, Fig. 2, to the inner end of the shifting-bar 33, whose outer end, as shown in Fig. 7, is formed with an elongated slot 34 to receive the bolt 35, Fig. 2, connecting the link 36 (by loose connection) with said bar 33 and which bolt 35 has applied upon its upper end the link 37, Figs. 10 and 11, connected with the cam-plates 38, the 20 latter being disposed one at each side of the shaft-bar 33 and having the oppositely-inclined cam-surfaces 39 40 and upper level surface 41, while at their inner ends the cam-plates 38 are recessed or cut away, as at 42, 25 Fig. 10. The level surface 41 of the cam-plates 38 is on a higher horizontal plane than the upper surfaces of the shifting-bar 33, and the said upper surface of said bar 33 is formed with the upwardly-projecting portion 43 and 30 seats 44 45, disposed at the ends of said portion 43, the said seats 44 45 having oppositely-beveled edges, as shown in Fig. 6, and adapted to receive the lower end of the locking-bar 46, which is also at its opposite lower 35 edges beveled off, as at 47, where said bar is to be contacted with by the inclined surfaces of the cam-plates 38. The shifting-bar 33 and cam-plates 38 are mounted to slide within a boxing 49, within which the locking-bar 46 is 40 adapted to have a vertical movement, said boxing 49 comprising a cap-section 50 and a base-section 51, the latter being recessed at its lower surface to fit upon the plate 52, rigidly mounted upon the beams or plates 53, 45 as shown in Fig. 1. The base 51 is also formed with apertures 54, as shown in Fig. 4, to receive the bolts by which said base may be rigidly fastened to the plate 52. The cap-section 50 of the boxing 49 is provided with 50 apertures 55 to receive the bolts by which said cap-section may be firmly secured to the base-section 51. Within the boxing 49 is formed the longitudinal passage for the shifting-bar 33 and cam-plates 38 and also a transverse 55 chamber to receive and permit the vertical movement of the locking-bar 46, the latter being guided upon vertical pins 56, Fig. 3, upon which are arranged the spiral springs 57, normally pressing the locking-bar 46 to 60 its downward position. (Shown in Figs. 2 and 3.) The cap-section 50 of the boxing 49 is formed with the longitudinal passage 58

for the detector-rod 59, this passage 58 being just above the upper level of the locking-bar 46 when the latter is in its lower position, as 70 shown in Fig. 2, so that when said rod 59 is in its locking position, as shown, the locking-bar 46 will be prevented from ascending from the switch-bar 33. The detector-rod 59 performs other duties, which will be hereinafter specified, in addition to serving as a means for locking the bar 46 in its lower position. 75

The outer end of the link 36 is pivotally secured to a bell-crank lever 60, Fig. 1, which is adapted to be operated for throwing the bar 80 33 and cam-plates 38 by the movement of a rod 61 of usual character and operable from a switch-stand of ordinary construction. (Not shown.)

The outer end of the detector-rod 59 is pivotally connected with the horizontal pivoted manually-operable lever 62, to which is connected the rod 63 for the signal apparatus 64, so that upon the movement of the said lever 62 the detector-rod 59 and signal-rod 63 may 90 have simultaneous movement, the purpose being that the signal apparatus 64 shall indicate by a color the condition of the switch. The lever 62 is provided at one end with a vertical handle 65, and this end of the lever 62 is confined within a horizontal frame 66, which limits the stroke of said lever. The lever 62 is formed with a small staple or eye 67, adapted to project through the end of the frame 66, as shown in Fig. 1, and to receive a padlock 68, which may be utilized for the purpose of locking the lever 62 in the position shown, so that the lever 62 may not be interfered with by meddlers. When the lever 62 is in its position shown in Fig. 1, its outer 105 end, carrying the handle 65, is directly over the handle end of the usual switch-lever 69 and prevents said switch-lever from being moved upward and over to its opposite position, this being an element of safety and requiring, 110 before the switch-lever 69 can be moved to move the rod 61 and throw the switch, the unlocking of the padlock 68 and the moving of the lever 62 to its opposite position, thereby, as a preliminary, shifting the detector-rod 59 115 and operating the rod 63 to effect the display of the proper signal at the apparatus 64, said apparatus 64 displaying red when the lever 62 is moved from the position shown and until said lever has been returned to the position shown. When the lever 62 is in the position in which it is illustrated in Fig. 1, the signal apparatus 64 will display a white light or color, indicating "safety."

The cam-plates 38 are set on edge and are 125 parallel to each other, and each of said plates at its outer end is formed with the upwardly-extending right-angular arm 70, as illustrated in Figs. 8 and 10, and the upwardly-extending arms 70 of the cam-plates 38 receive upon them the correspondingly-recessed transverse arm 71 of the link 37, said arm 71 being moved downward upon the said arms 70 and secured in position by a bolt or rivet 72, passing trans-

versely through apertures in said arms 70 71. The arms 70 71 not only aid in connecting the link 37 with the cam-plates 38, but in preserving the due parallelism of the cam-plates 38 and affording a convenient and durable structure.

The position of the parts illustrated in Fig. 1 is the normal correct position of the switch and operating mechanism when the cars are to travel on the main line, and in this position of parts it will be seen that the lever 62 at its outer end is over the handle of the switch-lever 69; that the shifting-bar 33 is in its outer position, with the switch-rail 21 against the rail 23; that the locking-bar 46 is in its lower position against its seat 44 on the shifting-bar 33; that the detector-rod 59 is above the locking-bar 46 and prevents the elevation of the latter, and that the signal apparatus 64 is in position to show the color white. When it is desired to shift the switch-rails 21 22 to their opposite position, the permanent attendant or a trainman from the train desiring to move on the side rails will free the padlock 68 and move the lever 62 to its opposite position and from over the switch-lever 69, thus withdrawing the detector-rod 59 from over the locking-bar 46 and, through the rod 63, setting the color red at the apparatus 64, whereupon the said attendant or trainman will throw the switch-lever 69 over to its other position and effect the movement of the rod 61 and bell-crank lever 60 with the result of, through the links 36 37, pushing the cam-plates 38 to elevate the locking-bar 46 from the seat 44 of the shifting-bar 33 and then driving said bar 33 through the boxing 49 for the purpose of, through the rod 24, shifting the switch-rails 21 22. The first portion of the movement of the rod 61, bell-crank lever 60, and link 37 is solely to actuate the cam-plates 38 for the purpose of moving their inclined surface 39 against the bevel edge of the locking-bar 46 to elevate said bar 46 in opposition to the force of its springs 57, and this movement of the cam-plates 38 takes place while the bolt 35 of the link 36 is traveling from the outer end of the elongated slot 34 of the bar 33 to the inner end of said slot, upon reaching which the said cam-plates 38 will have performed their duty and the bolt 35 will engage the wall at the inner end of said slot 34 and effect the movement of the shifting-bar 33, rod 24, and switch-rails 21 22. When the bar 33 is moved a sufficient distance to the left, the cam-plates 38 during the movement of the bar 33 traveling with the same, the bar 46 will descend upon the seat 45 of said bar 33, the inclined surfaces 40 of the cam-plates 38 then having gone beyond the said locking-bar 46. The engagement of the locking-bar 46 with the seat 45 of the shifting-bar 33 is for the purpose of locking said bar 46 and the parts operated therefrom, and it will be observed on reference to Fig. 2 that the seat 45 is on a somewhat-higher elevation than the seat 44, which in this sec-

ond position of the bar 33 leaves the upper edge of the locking-bar 46 partly closing the aperture 58 in the boxing 49 for the detector-rod 59. The shifting-bar 33 thus has two extremes of position, one being that illustrated in the drawings and the other being the position given to it by the rod 61 and bell-crank lever 60 when the locking-bar 46 engages the seat 45 of said bar 33. After the train has passed upon the side rails 22 23 the permanent attendant or a man from the train will return to the switch mechanism, throw the switch-lever 69 to its former position, being that shown, and then move the lever 62 until its outer end is above the handle end of the switch-lever 69, whereupon he will apply the padlock 68 for the purpose of locking the lever 62 in such position. During the return movement of the switch-lever 69 to its normal position shown the rod 61 will move outwardly and turn the bell-crank lever 60 for the purpose of withdrawing the shifting-bar 33 outwardly and moving the switch-rails 21 22 to the position in which they are shown in Fig. 1. During the first portion of the outward movement of the rod 61 the bell-crank lever 60 and link 36 will, through the bolt 35, first move the cam-plates 38 to elevate the locking-bar 46 from the seat 44 of the shifting-bar 33 and then said bolt 35, having reached the outer end of the slot 34, draw the shifting-bar 33 outwardly until at the limit of its movement the locking-bar 46 descends and engages the seat 44 of said bar 33, this outward movement of the bar 33, to the extent indicated, assuring the return of the switch-rails 21 22 to the position in which they are illustrated in Fig. 1. In the event that any obstruction or foreign substance should pass between the rails 21 23 when said rails are separated from each other and prevent the proper closing of the rail 21 against the rail 23 during the outward movement of the shifting-bar 33, this fact will be made apparent to the attendant or trainman attempting to operate the switch mechanism, because such obstruction or foreign substance would prevent the full outward movement of the shifting-bar 33, and therefore prevent the descent of the locking-bar 46 from the passage 58 of the boxing 49, and this detention of the locking-bar obstructing the said passage 58 would prevent the detector-bar 59 upon the movement of the lever 62 from passing through said boxing and above said locking-bar, the locking-bar when held in its upper position obstructing the passage 58 and blocking the movement of the rod 59. The rod 59 thus positively prevents the movement of the lever 62 to its normal position, (shown in Fig. 1,) and thus the attendant or trainman at the lever 62 would know by his inability to move said lever that the locking-bar 46 was in its upward position and that the rail 21 had not reached the rail 23. The rod 59 thus operates as a lock for the lever 62 and as a means for detecting that the locking-bar 46 and switch-rail 21 are out of position.

When the shifting-bar has moved to its full outward position, (shown in Fig. 2,) the locking-bar 46 will descend to the seat 44 and clear the passage 58, and at such time the detector-rod 59 may upon the movement of the lever 62 pass outward above said locking-bar 46, the rod 59 then serving to lock the bar 46 in its lower engaging position, in which position it will prevent the bar 33 from moving toward the left and secure the relation of the switch-rail 21 against the rail 23. In the operation of the switch mechanism the attendant or trainman must therefore first unlock the lever 62 and move it to release the switch-lever 69, withdraw the detector-rod 59 from over the locking-bar 46 and set the signal apparatus 64, and then throw the switch-lever 69 over for the purpose of actuating the operating-rod 61 and bell-crank lever 60 for moving the cam-plates 38 and shifting-bar 33, and in returning the switch-rails 21 22 to their former position the attendant or trainman must return the switch-lever 69 to its former position and thereafter move the lever 62 to its former position over the handle of said switch-lever 69, where it will be relocked by means of the padlock 68 or other suitable means. When the shifting-bar 33 and cam-plates 38 are in their normal position, (shown in Fig. 2,) the inner ends of said cam-plates will lie just at the right-hand edge of the chamber for the locking-bar 46, and when the said bar and cam-plates are moved toward the left the inner ends of said plates traverse the base of said chamber, and the recesses 42 in said ends enable the latter at such time to push from the boxing 49 any dust or like matter that may have passed down the side walls of said chamber. The recesses 42 aid materially in enabling the ends of the cam-plates 38 to push the dust and other foreign matter out from the boxing 49 and in preventing such dust from getting below the said cam-plates.

45 What I claim as my invention, and desire to secure by Letters Patent, is—

1. In a switch-operating mechanism, the shifting-bar having the seats in its upper side, the locking-bar adapted for engaging either of said seats, a cam-plate for moving said locking-bar outward from said seats, an operating-rod having a lost-motion connection with said shifting-bar, and a connection between said rod and said cam-plate, combined with the rod 59 adapted to pass over and prevent the elevation of said locking-bar when the latter is on one of its seats, and lever mechanism for shifting said rod 59 preparatory to the movement of said cam-plate and shifting-bar; substantially as set forth.

2. In a switch-operating mechanism, the shifting-bar having the seats in its upper side, the locking-bar adapted for engaging either of said seats, a cam-plate for moving said locking-bar outward from said seats, an operating-rod having a lost-motion connection with said shifting-bar, and a connection between

70 said rod and said cam-plate, combined with the rod 59 adapted to pass over and prevent the elevation of said locking-bar when the latter is on one of its seats, lever mechanism for shifting said rod 59 preparatory to the movement of said cam-plate and shifting-bar, and a connection between said rod 59 and the signal apparatus so that the latter may be operated simultaneously with said rod; substantially as set forth.

3. In a switch-operating mechanism, the shifting-bar having the seats in its upper edge on different planes, the locking-bar adapted 80 to engage either of said seats, a cam-plate for moving said locking-bar from said seats, an operating-rod having a lost-motion connection with said shifting-bar, and a connection between said rod and said cam-plate, combined 85 with the rod 59 adapted to pass over said locking-bar when the latter is on its lower seat, and lever mechanism for withdrawing said rod 59 from over said locking-bar when the shifting-bar is to be moved in one direction to carry its 90 higher seat below said locking-bar, and for returning said rod 59 to its position over said locking-bar when said shifting-bar has been moved back to its former position with its lower seat below said locking-bar; substantially as 95 set forth.

4. In a switch-operating mechanism, the shifting-bar having the seats in its upper edge on different planes, the locking-bar adapted 100 to engage either of said seats, a cam-plate for moving said locking-bar from said seats, an operating-rod having a lost-motion connection with said shifting-bar, and a connection between said rod and said cam-plate, combined 105 with the rod 59 adapted to pass over said locking-bar when the latter is on its lower seat, lever mechanism for withdrawing said rod 59 from over said locking-bar when the shifting-bar is to be moved in one direction to carry its higher seat below said locking-bar, and 110 for returning said rod 59 to its position over said locking-bar when said shifting-bar has been moved back to its former position with its lower seat below said locking-bar, and a connection between said rod 59 and the signal 115 apparatus so that the latter may be operated simultaneously with said rod; substantially as set forth.

5. A switch-operating mechanism comprising the shifting-bar having seats in its upper edge, the locking-bar adapted for engagement in either of said seats, the parallel cam-plates for moving said locking-bar upward and having the vertical arms at their outer ends, the link having the transverse notched arm to engage both of said vertical arms and also having a lost-motion connection with said shifting-bar, and an operating-rod connected with said link for shifting said cam-plates and shifting-bar; substantially as set forth.

6. A switch-operating mechanism comprising the shifting-bar having seats in its upper edge, the locking-bar adapted for engagement in either of said seats, the parallel cam-plates

38 at the sides of said shifting-bar for moving said locking-bar upward in advance of the movement of said shifting-bar and having the vertical recesses 42 in the outer sides of their 5 operating ends, means for moving said cam-plates and said shifting-bar, and the boxing affording a passage for said cam-plates and shifting-bar and a vertical chamber for said locking-bar, the recessed ends of said cam- 10 plates being adapted to push outward any dust or like matter which may fall upon the edges of the base of said chamber; substantially as set forth.

7. In a switch-operating mechanism, the 15 shifting-bar having the seats in its upper edge on different planes, the locking-bar adapted to engage either of said seats, and means for moving said locking-bar upward in advance of the movement of said shifting-bar, combined 20 with the rod 59 adapted to pass over said locking-bar when the latter is on its lower seat, and lever mechanism for withdrawing said rod 59 from over said locking-bar when the shifting-bar is to be moved in one direction 25 to carry its higher seat below said locking-bar, and for returning said rod 59 to its position over said locking-bar when said shifting-bar has been moved back to its former position with its lower seat below said locking- 30 bar; substantially as set forth.

8. In a switch-operating mechanism, the shifting-bar having the seats in its upper edge on different planes, the locking-bar adapted to engage either of said seats, and means for 35 moving said locking-bar upward in advance of the movement of said shifting-bar, combined with the rod 59 adapted to pass over said locking-bar when the latter is on its lower seat, lever mechanism for withdrawing said 40 rod 59 from over said locking-bar when the shifting-bar is to be moved in one direction to carry its higher seat below said locking-bar, and for returning said rod 59 to its position over said locking-bar when said shifting-bar 45 has been moved back to its former position with its lower seat below said locking-bar, and a connection between said rod 59 and the signal apparatus so that the latter may be operated simultaneously with said rod; substantially 50 as set forth.

9. In switch-operating mechanism, a shifting-bar connected with the switch-rails, a locking-bar for engaging said shifting-bar and holding the same against movement except 55 at the proper time, means for disengaging said locking-bar in advance of the movement of said shifting-bar, the operating-rod connected with said shifting-bar, and the switch-stand lever for moving said operating-rod, combined 60 with the rod 59 for disclosing whether said locking-bar, upon the movement and return of the switch-rails, has passed into its initial locking position with said shifting-bar, and lever mechanism for operating said rod 65 59; substantially as set forth.

10. In switch-operating mechanism, a shifting-bar connected with the switch-rails, a

locking-bar for engaging said shifting-bar and holding the same against movement except at the proper time, means for disengaging said locking-bar in advance of the movement of said shifting-bar, the operating-rod connected with said shifting-bar, and the switch-stand lever for moving said operating-rod, combined with the rod 59 for disclosing whether said locking-bar, upon the movement and return of the switch-rails, has passed into its initial locking position with said shifting-bar, lever mechanism for operating said rod 59, and a connection between said rod 59 and the signal apparatus so that the latter may be operated simultaneously with said rod; substantially as set forth.

11. In switch-operating mechanism, a shifting-bar connected with the switch-rails, a locking-bar for engaging said shifting-bar and holding the same against movement except at the proper time, means for disengaging said locking-bar in advance of the movement of said shifting-bar, the operating-rod connected with said shifting-bar, and the switch-stand lever for moving said operating-rod, combined with the rod 59 for disclosing whether said locking-bar, upon the movement and return of the switch-rails, has passed into its initial locking position with said shifting-bar, and the hand-lever connected with said rod 59 for operating the same, the said hand-lever when in its initial position holding the switch-stand lever against movement; substantially as set forth.

12. In switch-operating mechanism, a shifting-bar connected with the switch-rails, a locking-bar for engaging said shifting-bar and holding the same against movement except at the proper time, means for disengaging said locking-bar in advance of the movement of said shifting-bar, the operating-rod connected with said shifting-bar, and the switch-stand lever for moving said operating-rod, combined with the rod 59 for disclosing whether said locking-bar, upon the movement and return of the switch-rails, has passed into its initial locking position with said shifting-bar, the hand-lever connected with said rod 59 for operating the same, and means for locking said hand-lever when in its initial position in proper relation to prevent movement of said switch-stand lever; substantially as set forth.

13. In switch-operating mechanism, a shifting-bar connected with the switch-rails, a locking-bar for engaging said shifting-bar and holding the same against movement except at the proper time, means for disengaging said locking-bar in advance of the movement of said shifting-bar, the operating-rod connected with said shifting-bar, and the switch-stand lever for moving said operating-rod, combined with the rod 59 for disclosing whether said locking-bar, upon the movement and return of the switch-rails, has passed into its initial locking position with said shifting-bar, the hand-lever connected with said rod 59 for operating the same, the rod connecting said

hand-lever with the signal apparatus, and means for locking said hand-lever when in its initial position in proper relation to prevent movement of said switch-stand lever; 5 substantially as set forth.

14. In switch-operating mechanism, a shifting-bar connected with the switch-rails, a lock for holding said bar in its initial position, means for disengaging said lock to permit the movement of said shifting-bar, and means for operating said shifting-bar, combined with manually-operable means for disclosing whether said lock, upon the movement and return of the switch-rails, has 15 passed into its initial locking position with said shifting-bar; substantially as set forth.

15. The switch-rails, and means for shifting the same combined with the head-rod connecting said rails and comprising the 20 threaded rod 24, bars 25, 26, connected with said rails and having the right-angular members 28 receiving said rod 24, and the securing-nuts on said rod 24 at opposite sides of said members 28; substantially as set forth.

25 16. The switch-rails, and means for shifting the same combined with the head-rod

connecting said rails and comprising the threaded rod 24, bars 25, 26, connected with said rails and having the right-angular members 28 receiving said rod 24, and the securing-nuts on said rod 24 at opposite sides of said members 28, the said members 28 at their lower ends extending laterally to lock the nuts at one side thereof; substantially as set forth. 30

17. The switch-rails, the shifting-bar and lever mechanism for operating said bar, combined with the rod 24 threaded at its inner end and at its outer end connected with said shifting-bar, the bars 25, 26 connected with 40 the said rails and having the angular members 28 receiving the threaded portion of said rod, and the nuts on said rod at opposite sides of said members 28; substantially as set forth. 45

Signed at New York, in the county of New York and State of New York, this 2d day of January, A. D. 1903.

EDWARD W. COUGHLIN.
